[57] CLAIM

The ornamental design for a combined cabinet soffit and plate support unit, as shown and described.

DESCRIPTION

FIG. 1 is a bottom perspective view of a combined cabinet soffit and plate support unit showing my new design with the plate support in an alternate embodiment.

FIG. 2 is a sectional view taken along line 4—4 of FIG. 1, further showing the plate support and its design relationship to the soffit.

The design of the opposite side of the combined cabinet soffit and plate support unit is the same as that of the side shown, and the design of the back thereof is the same as the design of the face thereof, or plain.
